UNITED STATES PATENT OFFICE.

LEWIS GIBBS, OF CANTON, OHIO.

LAWN-RAKE.

SPECIFICATION forming part of Letters Patent No. 314,373, dated March 24, 1885.

Application filed October 3, 1884. (No model.)

To all whom it may concern:

Be it known that I, LEWIS GIBBS, of Canton, in the county of Stark and State of Ohio, have invented certain new and useful Improvements in Lawn-Rakes; and I do hereby declare the following to be a full, clear, and exact description of the invention, such as will enable others skilled in the art to which it pertains to make and use the same.

10 My invention relates to improvements in lawn-rakes, the object being to improve the construction and to reduce the initial cost of these utensils.

With this object in view my invention consists in certain features of construction and combination of parts, hereinafter described, and pointed out in the claims.

In the accompanying drawings, Figure 1 is a view in perspective of my improved lawn-rake. Fig. 2 is a view in perspective of the under side of the rake. Fig. 3 is a view in perspective of the handle-socket and attachments. Fig. 4 is an enlarged view in perspective of a portion of an end piece. Fig. 5 is a 25 view in perspective of an entire end piece. Fig. 6 is a view in perspective of one of the braces. Fig. 7 is a transverse section of the rake-head. Fig. 8 is a view in perspective of a portion of the rake-head with parts broken 30 away to show the construction. Fig. 9 is a side view in elevation of a rake-tooth.

A represents the wooden handle that is secured in the skeleton socket A'. This socket terminates in the shank A², that is bent at the 35 end, as shown, and hooks over the head of the rake, and is secured thereto at A³. The socket part is provided with the points a, that, after the handle is in position, are bent around the handle, and are hammered down to embed the points more or less in the wood, thereby firmly securing the handle from pulling out endwise. If the handle, from shrinkage or other cause, should become loose, a blow 40 on these points will bend them down still farther and tighten the handle. This skeleton is therefore a great improvement on the ordinary socket, that in cross-section is an entire circle. On the sides of the socket are the ears a' for attaching the braces B. On the under 45 side of the shank are the depending points a² and a³. The former are bent under the edges of the board C, as shown at Fig. 2, and the latter is driven through the same board and clinched. The braces B are riveted to the ears a', and have depending points b, that are 50 bent under the edge of the board C, and the braces at the end at b' are secured by a screw or nail to the rake-head. The head of the rake is formed of the pieces C, D, and E, to which are added the metal end pieces, F, and 55 the teeth G. The teeth are shown clearly in Fig. 9, and consist each of a single piece of wire bent as there shown. The wooden piece D has a series of slight grooves, d, to receive the shanks of the teeth, and have small holes 60 d', in which the points g of the teeth enter. When the teeth are pressed or driven home, the wire fits snugly in the grooves d, and the ends g of the teeth are forced firmly into the wood. The part E is then secured to the 65 face of the part D, by means of which the teeth are held in place, after which the part C is placed in the position shown, and secured to the parts D and E by nails, screws, or other means. The end pieces, F, are preferably of 70 malleable iron, and made right and left handed, and have a rib, f, that lies on top of the part C, and lips f², arranged preferably in pairs to embrace the part C, and may have 75 teats f', that may be indented into the wood 80 to hold the end piece from drawing off of the part C. The end piece is also secured by a screw, c². The lower end, F', is curved to correspond with the part g' of the teeth, and form runners to slide along the ground. The teeth 85 are bent in such shape that when the rake is held in position for work the points of the teeth are elevated a short distance above the ground, so that each tooth forms a runner and slides along the ground, and there is no part of the 90 rake that scrapes the surface of the ground, and therefore there is no possibility of injuring the grass-roots. The points of the teeth are so near the ground that they pass under leaves, grass, or anything lying loose on the surface. The 95 teeth are preferably of steel wire, and are quite elastic, and consequently are not easily broken. The teeth are of considerable length, and the board C is of considerable width, so that the rake has sufficient capacity for leaves and other 100 light litter that is usually to be removed from lawns. The teeth being single, if one is broken

or injured, it is easily and cheaply replaced, and a few extra teeth may be furnished with each rake at a mere nominal extra cost.

The construction is such that the rake is light and strong, and may be made at a small initial cost.

I am aware that it is not broadly new to connect the rake-head to the handle by an intervening metallic socket, and also that it is not broadly new to strengthen the connection between the handle and head by side braces; but what I claim is—

1. In a lawn-rake, a handle-socket terminating in a shank for attachment to the rake-head, and bent at the end so as to hook over the side of the head, and provided with ears for the attachment of braces and with points adapted to engage the wood-work and to be clinched, substantially as set forth.

2. In a lawn-rake, a skeleton socket for a handle semicircular in cross-section, and provided on the edges with depending points for bending around and securing the wooden handle, and the socket terminating in a shank for attachment to the rake-head, substantially as set forth.

3. In a lawn-rake, a tapering skeleton socket for a handle with depending points adapted to be bent around the wooden handle, and the socket provided with lugs or ears for the attachment of braces, and terminating in a shank for attachment to the rake-head, and braces riv-

eted to said ears and secured to the rake-head, substantially as set forth.

4. In a lawn-rake, the combination, with 35 braces provided with points for clinching to the rake-head, of a handle socket and shank provided with ears or lugs for attaching the braces, substantially as set forth.

5. In a lawn-rake, wire teeth, preferably of 40 spring-steel, and each tooth separate from the other teeth and bent back near the upper end at about a right angle, the ends of which are adapted to be forced into the wood and the lower end curved forward and upward, so as 45 to form runners, with the points of the teeth slightly elevated from the ground when the rake is held in working position, substantially as set forth.

6. In a lawn-rake, the part D, provided with 50 the grooves d and the holes d', in combination with the teeth G and the strip E, substantially as set forth.

7. In a lawn-rake, the combination, with the parts D and E and the teeth G, of the part 55 C and the ends F, substantially as set forth.

In testimony whereof I sign this specification, in the presence of two witnesses, this 22d day of September, 1884.

LEWIS GIBBS.
